PETER J. JORGENSEN AND CLARENCE H. JORGENSEN, OF CHICAGO, ILLINOIS

THERMOSTATIC CONTROLLING DEVICE

Application filed August 2, 1930. Serial No. 472,847.

This invention relates to thermostatic controlling devices and has for its object to provide a new and improved device of this description. The invention has as a further object to provide a thermostatic controlling device particularly adapted to be used in connection with the cooling system of an internal combustion engine. The invention has as a further object to provide a thermostatic controlling device for use in the cooling circulatory system of an internal combustion engine, arranged so that the valve controlled by the thermostat will be delayed in the starting of its opening and will then be quickly fully opened so as to delay the starting of the opening of the valve until the temperature reaches a higher point than is ordinarily the case, and then to complete the opening of the valve through a much shorter range of temperature than is ordinarily the case. The invention has as a further object to provide a device of the kind described wherein the range of temperature between the starting of the opening of the valve and its complete opening is confined to a comparatively small range. The invention has further objects which are more particularly pointed out in the accompanying description.

Referring now to the drawing, Fig. 1 shows an internal combustion engine provided with one form of apparatus embodying the invention;

Fig. 2 is an enlarged sectional view through the support for the valve controlled by the thermostat;

Fig. 3 is a sectional view taken on the line 3-3 of Fig. 2;

Fig. 4 is a side elevation of the support for the valve.

Like numerals refer to like parts throughout the several figures.

Referring now to the drawing, we have shown an internal combustion engine 1, a water jacket 2 having a connection 3 extending to the radiator 4, the radiator having a connection 5 leading back to the water jacket. A pump 6 is provided which pumps the cooling fluid through the cooling circulatory system. Located within the con-

nection 3 is a controlling device for controlling the circulatory system. This controlling device as herein shown consists of a valve 7 pivoted at 8 and 9 with a support 10. This support is shown as a cylindrical member having a flange 11 by means of which it is held in place, the flange being clamped between the flanges 12 and 13 of the portions of the connection 3, as shown in Fig. 1. A thermostatic member 14, made up of any suitable material, has an end portion 15 which is connected with the valve 7 at a point at one side of its pivotal connection with its support. This connection may be made in any desired manner. As herein shown, the end 15 is connected by a pivot 16 with a link 17 which projects through an opening in the valve, and which is connected by a pivot 18 with the housing 19 attached to the side of the valve. This housing completely covers the opening in the valve to prevent any leakage therethrough. The thermostatic member is shown as a coiled member with its end connected to a shaft 14a mounted in the projections 14b extending from the support 10.

The pump forces the cooling liquid in the direction of the arrow shown in Fig. 2. Connected with the support 10 on the side of the valve 7 opposite to that on which the thermostatic member is located, is a baffle 20 which is shown with its inner end inclined toward the valve. This baffle may be formed in any desired manner and as herein shown consists of a plate inserted in a slot in the support 10. This support is provided with one or more open slots 21 intermediate the baffle 20 and the valve 7. The valve 7 is provided with an opening 22 arranged so that liquid which passes through it when the valve is closed will strike the baffle 20 and be directed through the openings 21.

When the valve 7 is opened to its full open position, it strikes the end 15 of the thermostatic element and this end acts as a stop to prevent the valve from further movement and to insure the full open position without permitting the valve to move beyond this full open position.

The use and operation of our invention are as follows:

When the device is in position as shown in Fig. 1 and the engine is not running, the valve 7 is closed as shown in Fig. 2. If now the engine is started up, the pump 6 is set in operation and tends to circulate the liquid in the cooling circulatory system. The valve 7, however, prevents this circulation and holds the cooling fluid in the water jacket around the cylinder. Until this cooling fluid is heated, this holding of the fluid in this position causes the engine to heat up quickly, which is the thing desired. When the cooling fluid reaches a predetermined temperature, it acts upon the thermostatic element 14 so as to cause it to move the valve 7 towards its open position and permit the circulation of the cooling fluid through the radiator, due to the action of the pump 6.

Now there are certain difficulties in connection with a thermostatic device of this description which the present construction is arranged to overcome. In the ordinary thermostatic device it takes a change in temperature of from 40 to 50 degrees to move the valve from its closed to its open position. This means that if the valve is fully opened at the proper time, it must start to open altogether too soon for the present practice. That is, it must start to open before the temperature of the engine has been brought up to a sufficient height. Furthermore, if the thermostat is set to start to operate when the temperature has reached the height desired, then the valve is not fully opened until the temperature becomes too high. This is particularly objectionable when alcohol is used as the cooling liquid, due to the fact that the alcohol boils at a comparatively low temperature. For example, if the thermostat takes 40 to 50 degrees change in temperature to move the valve from its closed to its open position, it will be necessary to arrange the device so that it will start to open at, say 130 to 135 degrees so that it would be fully opened before the temperature reached, say 175 degrees F., which is approximately the boiling point of alcohol.

With the present construction the variations in temperature required between the starting of the opening of the valve and the complete opening is very greatly reduced, and instead of having the valve start at, say 130 to 135 degrees, with the present device it can be arranged to start to open the valve at 150 to 160 degrees, and still fully open it before the temperature gets too high or before the temperature reaches the boiling point of alcohol. In other words, with the present device the range of variation in temperature between the point where the valve starts to open and is

completely opened is reduced to 12 or 15 degrees. This condition is brought about by the arrangement of the baffle 20. The thermostat can be set to start to open the valve at the desired higher temperature. When the valve starts to open, due to the thermostat being brought to the desired temperature, the cooling liquid passes by it by its edge and strikes the baffle 20 and then rebounds and strikes the side of the valve opposed to the baffle, and this tends to open the valve with a force additional to that applied by the thermostatic element. As the valve opens more, more cooling liquid strikes the baffle 20 and more force is applied to the valve by the rebounding liquid tending to open it, and hence the liquid itself is used to help open the valve. By this arrangement the valve can be completely opened through a very short range of temperature variation for the thermostat.

We have found that it seems to be desirable to have the baffle 20 project quite a distance along the valve 7, and that when the valve begins to open it will then be produced to greater force by the rebounding liquid, tending to open it at the start. To prevent this we have provided the openings 21, so that a part of this liquid passes through these openings, thereby reducing the opening effect of the rebounding liquid. When the valve is opened, a greater amount, the quantity of water is so increased that the amount going through these openings becomes practically negligible.

We have found that in practice it is often desirable to provide a small opening 22 in the valve 7, as shown in Fig. 2. This is due to the fact that the pump in operation causes considerable pressure on the valve 7 and on the pivots of said valve, particularly where high pressures are used, and this tends to make the temperature run up too high before the valve starts to open. By means of this opening 22, this difficulty, we find, is overcome, for by its use a slight unbalancing effect is produced when the valve is in its closed position and this unbalancing effect is brought about without upsetting the balanced condition after the valve has left its seat.

It will therefore be seen that with the construction herein shown the valve 7 is held closed through a longer period and until the temperature of the engine has reached a comparatively high point. The thermostat then starts to open the valve and the liquid, flowing past the edge of the valve, striking the baffle 20, rebounds and applies an opening force to the valve to help open it, this force being in addition to that applied by the thermostat. In fact, it can be arranged so that this force will overcome any backward pull that the thermostat might have on the valve, so that by proper

proportioning of the parts, the valve can be opened to its full open position through a short range of temperature after it has started to open. This range of temperature 5 is controlled by the proper arrangement of the parts.

It is of course evident that the temperature at which the valve opens can be regulated as desired, and we have simply 10 referred to certain degrees of temperature for the purpose of making our invention clear. It will further be seen that with this construction the valve may be pivotally mounted at its center so as to be balanced, 15 and still such valve can be held closed until the desired temperature is reached and can then be quickly opened. It will also be seen that by means of this construction the parts can be arranged so that there will be no 20 danger of an over run of the temperature before the valve opens.

We claim:

1. A thermostatic controlling device comprising a valve, a support therefor having a 25 passageway closed by said valve, a thermostatic element connected with said valve for moving said valve in response to variations in temperature, a baffle projecting into said passageway and against which the liquid 30 flowing past the valve while it is being opened strikes said liquid rebounding and striking the valve so as to apply an opening pressure to it.

2. A thermostatic controlling device comprising a valve, a support therefor having a 35 passageway closed by said valve, a thermostatic element connected with said valve for moving said valve in response to variations in temperature, a baffle projecting into said 40 passageway and against which the liquid, flowing past the valve while it is being opened strikes said liquid rebounding and striking the valve so as to apply an opening pressure to it, and a liquid discharge opening 45 in said support between the baffle and the valve.

3. A thermostatic controlling device comprising a valve, a support therefor having a 50 passageway closed by said valve, a thermostatic element connected with said valve for moving said valve in response to variations in temperature, a baffle projecting into said 55 passageway and against which the liquid flowing past the valve while it is being opened strikes said liquid rebounding and striking the valve so as to apply an opening pressure to it, the valve being provided with an opening in the portion thereof in proximity to said baffle.

4. A thermostatic controlling device comprising a valve, a support therefor having a 60 passageway closed by said valve, a thermostatic element connected with said valve for moving said valve in response to variations 65 in temperature, a baffle projecting into said

passageway and against which the liquid flowing past the valve while it is being opened strikes said liquid rebounding and striking the valve so as to apply an opening pressure to it, and a liquid discharge opening 70 in said support between the baffle and the valve, the valve being provided with an opening in the portion thereof in proximity to said baffle.

5. A thermostatic controlling device comprising a valve, a support therefor having a 75 passageway closed by said valve, a thermostatic element connected with said valve for moving said valve in response to variations in temperature, and means for utilizing the pressure of liquid after it has passed the 80 valve to apply an opening pressure to said valve.

6. A thermostatic controlling device comprising a valve, a support therefor having a 85 passageway closed by said valve, a thermostatic element connected with said valve for moving said valve in response to variations in temperature, and means for utilizing the pressure of liquid after it has passed the 90 valve to apply an opening pressure to said valve, and means for reducing the effectiveness of this pressure at the beginning of the opening of the valve.

7. A thermostatic controlling device comprising a valve, a support therefor having a 95 passageway controlled by said valve, said valve pivotally connected near its middle with said support, a thermostatic element 100 mounted in alignment with said valve and connected therewith at one side of the pivotal connection, and means for utilizing the pressure of liquid after it has passed the valve to apply an opening pressure to said valve on the other side of said pivotal connection.

8. A thermostatic controlling device comprising a valve, a support therefor having a 110 passageway controlled by said valve, said valve pivotally connected near its middle with said support, a thermostatic element mounted in alignment with said valve and connected therewith at one side of the pivotal connection, means for utilizing the pressure of liquid after it has passed the valve 115 to apply an opening pressure to said valve on the other side of said pivotal connection, and means for reducing the effectiveness of said pressure at the beginning of the opening of the valve.
